D2-506

EX

07448

OR D 23,437

DESIGN.

P. COX.
HANDKERCHIEF.

No. 23,437.

Patented July 10, 1894.

WITNESSES:

Andrew McFadd
Charles Hobson

INVENTOR

Palmer Cox.

UNITED STATES PATENT OFFICE.

PALMER COX, OF NEW YORK, N. Y.

DESIGN FOR A HANDKERCHIEF.

SPECIFICATION forming part of Design No. 23,437, dated July 10, 1894.

Application filed February 19, 1894. Serial No. 500,798. Term of patent 14 years.

To all whom it may concern:

Be it known that I, PALMER COX, a citizen of the United States, and a resident of the city, county, and State of New York, have invented and produced a new and original Design for a Handkerchief or Similar Article of Textile Fabric, of which the following is a full, clear, and exact specification, reference being had to the drawing forming part thereof.

10 The object of my invention is to produce a design such as is not only new and original but also has a pleasing effect to the eye which is peculiar to itself, thus being attractive and popular.

15 My design as shown in the drawing is produced on woolen, silk, cotton and other fabrics.

The drawing represents a handkerchief or similar article on which is shown my design.

20 The leading feature of this design consists in the figure of a Policeman Brownie which falls entirely within a circular outline or circumference of the center and forms a center of attraction when viewed in connection with the other Brownie figures which are grouped

25 around as follows: First. Arranged within a line separating the center from the border appears an Irishman Brownie with an innocent expression on his face arranged at an angle to the Policeman Brownie whose expression as he eyes the Irishman is one of hesitation for 30 fear of being mistaken in the guilt of the Irishman Brownie. Secondly. Likewise arranged, at an angle to and beneath the Policeman Brownie appears a Soldier Brownie with his eyes turned toward the Irishman Brownie as 35 though amused and in doubt as to the Irishman's guilt. Thirdly. Likewise arranged at an angle to and above the Policeman Brownie appears a German Brownie with consternation pictured on his face as though he feared the 40 policeman. Fourthly. Likewise arranged, at an angle to and above the Policeman Brownie appears an ordinary Brownie delighted at the surroundings.

Some of the figures are drawn to represent 45 the characteristic dress of a peculiar country, thus serving to instruct the young, while the design affords pleasure and amusement to both young and old.

I claim—

50 The design for a handkerchief or similar article substantially as herein shown and described.

PALMER COX.

Witnesses:

A. M. TODD,
CHARLES S. POTSDAM.